Kevin Prince(57) **CLAIM**

We claim the ornamental design for a portable air inflation device, as shown and described.

DESCRIPTION

FIG. 1 is a top perspective view of a portable air inflation device, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a bottom perspective view thereof.

The broken lines are included for the purpose of illustrating portions of the portable air inflation device that form no part of the claimed design.
